REFRIGERATION

Alfred G. Gross, Chicago, Ill., assignor to The Hoover Company, North Canton, Ohio, a corporation of Ohio

Application May 22, 1939, Serial No. 274,869

14 Claims. (Cl. 62—119.5)

This invention relates to the art of refrigeration and more particularly to a novel three-fluid absorption refrigerating system.

In previous three-fluid absorption refrigerating systems it is customary to supply liquid refrigerant to an evaporator through which the liquid flows in a thin stream in contact with a gas stream. This possesses the disadvantage that the area of liquid to metal contact is extremely small as the stream of liquid flowing through the evaporator amounts only to a thin trickle. Also the area of gas and liquid contact is extremely small as the surface of the trickle of liquid refrigerant flowing through the evaporator amounts to but a small fraction of the interior surface area of the evaporator conduit. This arrangement produces an inefficient apparatus because heat transfer between the inert gas and the metal wall of the evaporator conduit is poor and the area of the conduit which is wetted by the liquid is small as noted above, wherefore inefficient evaporation results and a sharp temperature differential is maintained between the exterior wall of the evaporator and the gas stream flowing therethrough. In addition to the above factors the gas stream is discharged from the evaporator at a very low temperature which represents just so much wasted refrigerative effort.

Various means have been utilized in an attempt to remedy this condition but all of these means cause additional complications in the apparatus and are only indifferently successful. Among such means may be mentioned the provision of wicking material in the evaporator, the insertion of metal wires and the insertion of metal ribbons. These devices tend to distribute the liquid refrigerant but they impede the flow of the inert gas, require a larger conduit, add very greatly to the cost of the evaporator and they form an additional link in the path through which the heat is conducted from the exterior walls of the evaporator to the liquid refrigerant therein contained. The net result of these constructions is that the additional length of the heat conducting path and the additional flow resistance practically offsets the advantages gained by enlarging the area of the liquid refrigerant in contact with the inert gas.

Accordingly, it is a principal object of the present invention to provide an evaporator in which an unbroken film of liquid refrigerant is maintained uniformly throughout the extent of the evaporator upon and across which the inert gas flows whereby to provide direct liquid to metal heat transfer throughout the entire extent of

the evaporator wall and also to provide the maximum possible gas and liquid heat contact area without the introduction of any structural elements into the interior of the evaporator conduit which would tend to impede the heat transfer or to interfere with the gas flow therethrough.

It is another object of the invention to provide a three-fluid absorption refrigerating system in which the liquid refrigerant circulates through the evaporator by gas lift action in contact with the gas into which it evaporates.

It is another object of the present invention to provide a three-fluid absorption refrigerating system in which the liquid refrigerant is circulated through an evaporator having a pair of distinct sections by twin gas lift pumping action.

It is a further object of the present invention to provide a three-fluid absorption refrigerating system with an evaporator consisting of a pair of parallel connected substantially identical or, if preferred, non-identical sections through which the liquid refrigerant is circulated by gas lift action and in which the two sections of the evaporator conduit operate on the twin gas lift pump principle.

It is a further object of the invention to provide a three-fluid absorption refrigerating system including an evaporator which is practically independent of the elevation at which the condenser is located.

It is another object of the invention to provide a refrigerating system in which a very large body of cold liquid refrigerant is continuously circulated through the evaporating portion of the apparatus.

It is another object of the present invention to provide a three-fluid absorption refrigerating system in which foreign bodies, such as absorption solution finding their way into the evaporator are continuously removed therefrom.

It is a further object of the present invention to provide a three-fluid absorption refrigerating system including an evaporator operating on the gas lift pump principle and including a relatively large body of liquid refrigerant which is recirculated through the evaporator with means to continuously remove accumulated strong solution from the re-circulating material.

It is a still further object of the present invention to provide a three-fluid absorption refrigerating system in which spaced bodies of gas circulate through the evaporator alternating with spaced bodies of liquid and in contact with a thin film of liquid which adheres to the entire inner wall of the evaporator conduit.

Other objects and advantages of the invention will become apparent as the description proceeds when taken in connection with the accompanying drawing, in which the single figure of the drawing illustrates diagrammatically a refrigerating system embodying the present invention and in which the evaporator and certain associated portions thereof are illustrated in perspective and on an enlarged scale.

Referring now to the drawing in detail, there is illustrated a three-fluid absorption refrigerating system comprising a boiler B, an analyzer D, an air-cooled rectifier R, a tubular air-cooled condenser C, an evaporator E, a gas heat exchanger G, an inclined tubular air-cooled absorber A, a liquid heat exchanger L, a solution reservoir S, and a circulating fan F which is driven by an electrical motor M. These elements are suitably interconnected by various conduits to form a complete refrigerating system including a number of gas and liquid circuits to which reference will be made in more detail hereinafter.

The above mentioned refrigerating system will be charged with a suitable refrigerant, such as ammonia, a suitable absorbent therefor, such as water, and an inert pressure equalizing medium, preferably a dense inert gas like nitrogen.

The boiler B may be provided with any suitable heating means, such as an electrical cartridge heater, a gas burner or a liquid fuel burner.

The application of heat to the boiler B generates refrigerant vapor from the refrigerant absorbing solution therein contained. The vapor so generated passes upwardly through the analyzer D in counterflow to strong solution flowing downwardly therethrough whereby further refrigerant vapor is generated by the heat of condensation of absorption solution vapor carried into the analyzer. The refrigerant vapor is then conveyed from the analyzer D to the upper portion of the condenser C by means of a conduit 11 which includes the rectifier R.

The weak solution formed in the boiler by the generation of refrigerant vapor therefrom is conveyed from the boiler to the solution reservoir S by way of the conduit 14, the liquid heat exchanger L and a finned pre-cooling conduit 16. The liquid level prevailing in the boiler-analyzer reservoir system is appreciably below the upper portion of the absorber wherefore a gas lift pump conduit 17 is provided to convey the lean solution from the bottom portion of the reservoir S into the upper portion of the absorber A. A small gas bleed conduit 18 is connected between the discharge conduit 19 of the circulating fan F and the gas lift pump 17 below the liquid level normally prevailing therein in order to supply pumping gas to the conduit 17. The upper portion of the solution reservoir S is vented by means of a small conduit 20 to the conduit 21 which is connected directly to the suction side of the circulating fan F whereby the gas lift pump is enabled to operate with the maximum pressure differential available in the system.

The lean solution supplied to the absorber A flows downwardly therethrough by gravity in counterflow relationship to a mixture of pressure equalizing medium and refrigerant vapor which flows upwardly therethrough and is supplied from the evaporator. The solution absorbs the refrigerant vapor content of the mixture and the heat of absorption is rejected to cooling air flow-

ing across the fins provided on the exterior walls of the absorber conduit.

The strong solution which is formed in the absorber as a result of the absorbing action flows to the bottom portion thereof from which point it is conveyed to the upper part of the analyzer D by way of the conduit 23, the liquid heat exchanger L, and the conduit 25.

The lean inert gas formed in the absorber is conveyed from the upper end thereof through the pipe 21 into the suction side of the circulating fan F in which it is placed under pressure and is discharged through the conduit 19 into the outer path of the gas heat exchanger G from which the lean gas is conveyed by means of the conduit 26 into the bottom portion of the evaporator E.

The refrigerant vapor which is supplied to the condenser C by way of the conduit 11 is liquefied in the condenser and is discharged therefrom into a reservoir and separation vessel 28 by means of a conduit 29. The liquid refrigerant is conveyed from the reservoir into the bottom portion of the evaporator in a manner to be described in more detail hereinafter. For the present it is sufficient to note that the liquid refrigerant and inert gas flow upwardly through the evaporator as the refrigerant is evaporating thereinto to produce refrigeration. The evaporator E also includes an upper finned tubular box-cooling section 30 which discharges into the vessel 28. The rich gas is then conveyed from the vessel 28 to the inner path of the gas heat exchanger G by means of the conduit 31 and is conveyed from the inner path of the gas heat exchanger G to the bottom portion of the absorber A by means of the conduit 32. The inert gas refrigerant vapor mixture flows upwardly through the absorber A in counterflow to the absorption solution in the manner heretofore described.

Specifically considered, the evaporator E comprises a pair of similar sections which are formed of a continuous piece of tubing or of a plurality of pre-formed sections of tubing which are suitably joined as by welding. As illustrated, the evaporator comprises a right-hand section 35 and a left-hand section 36. As these two sections of the evaporator are identical, a description of one will suffice for a description of both. Referring now to the right-hand section 35 of the evaporator the same comprises a pair of lower and upper rearwardly directed horizontal parallel U-shaped conduits 38 and 39, respectively, which are connected at their rear outer sides by means of a riser conduit 40. The inner leg of the U-shaped conduit 39 is connected to a single overlying forwardly directed conduit 41 by means of a riser 42. The forward end of the conduit 41 is connected by a short riser 43 into the box-cooling conduit 30 and on the right hand side of a central partition 44. The upper end of the evaporator section 35 terminates on the left hand side of the partition 44. There is then formed a coil arrangement including two horizontally positioned coil sections each comprising two U-shaped conduits 38 or 39 which are well adapted when enclosed in a suitable casing to support ice trays or ice tray supporting shelves in order to produce low temperature refrigeration. The conduit 41 will also aid in refrigerating material supported upon the coils 38.

The inner bottom legs of the U-shaped conduits 38 of the coil sections 35 and 36 are serially connected by a U-shaped conduit 47 which

extends downwardly below the plane of the conduit 38 a slight distance. Each leg of the U-shaped conduit 47 is connected to one end of an inverted U-shaped conduit 48 which is connected to the inert gas supply conduit 28.

The liquid refrigerant which accumulates in the vessel 28 is conveyed therefrom into the bight portion of the conduit 47 by means of a conduit 50 which extends into the vessel 28 and terminates in a downwardly facing goose-necked end portion 51 at approximately the mid point of the vessel 28.

The vessel 28 includes a trapping and separation cup 53 positioned adjacent the discharge point of the box-cooling conduit 38 in order to receive liquid refrigerant flowing therethrough. A conduit 54 is arranged to convey liquid material supplied to the cup 53 in the vessel 28 by the box-cooling conduit 38 to the bottom portion of the vessel 28.

The evaporator and the U-shaped conduit 47 may be constructed either from a continuous piece of tubing bent to a suitable shape or it may be constructed from a plurality of pre-formed tubing sections suitably secured together as by welding, brazing or the like.

A purge conduit 60 extends from a point closely adjacent the bottom wall of the compartment 28 upwardly about three-fourths of the vertical height thereof and then turns rearwardly, as viewed in the drawing, passing through the rear wall of the vessel 28, after which the conduit 60 extends downwardly and terminates in communication with the rich solution return conduit 23. A small vent conduit 62 opens into the highest portion of the conduit 60 which is within the vessel 28 and terminates in the upper gas containing portion of the vessel 28.

The apparatus will be charged with a refrigerant absorbent and inert gas in the usual manner with the following exceptions. The vessel 28 will be charged directly with liquid refrigerant up to approximately the level of the point of connection between the conduits 60 and 62.

The operation of the invention except as the same has been described hereinabove is as follows: When the apparatus is initially charged the liquid refrigerant stands in the vessel 28 and in the evaporator E at a level corresponding approximately to the level of the point of connection between the conduits 60 and 62. When the control mechanism energizes the heater for the boiler and the electrical motor M, inert gas is supplied to the U-shaped conduit 47 through the conduit 48. The gas thus supplied alternately discharges from the legs of the U-shaped conduit 48 into the legs of the U-shaped conduits 47 which are connected with the evaporator sections 38 and 36 and the liquid refrigerant therein is elevated therethrough by twin gas lift action, that is, a slug of gas alternately enters the right and left hand sides of the U-shaped conduit 47 whereby the liquid refrigerant will discharge from the evaporator sections 38 and 36 alternately into the conduit 60 on opposite sides of the partition 44.

It has been found from long experience in operating the type of system herein disclosed that small quantities of absorption solution will find their way into the evaporator and that these must be removed before too great an accumulation is permitted. A strong solution of ammonia and water has a greater density than a weak solution thereof or than pure ammonia and in such a system the strong solution tends to settle at

the bottom of the containing vessel. This phenomena is facilitated if the conditions prevailing in the vessel are relatively static. The present invention takes advantage of this phenomena by returning the solution which is circulated through the evaporator directly to the bottom portion of the vessel 28 and by directing the fresh solution through the conduit 28 at a point relatively adjacent the bottom portion of the vessel 28. Absorption solution which finds its way into the evaporator is continually returned to the bottom portion of the vessel 28 by the conduit 54. The goose neck 51 feeds refrigerant liquid rising from the bottom of the vessel and supplied from the conduit 28 which has a very low absorption solution concentration into the evaporator.

The twin gas lift pump per se is disclosed and claimed in the co-pending application of Curtis C. Coons and Rudolph S. Nelson, Serial No. 169,986, filed October 20th, 1937. It is characteristic of this type of pump that there is provided an oscillating column of liquid in the bight portion of the U-shaped conduit 47. This oscillating body of liquid is believed to be largely responsible for the remarkable efficiency of the twin gas lift pump.

Thus, in a broad sense, the liquid refrigerant is circulated through the evaporator by gas lift action; that is, the low density column of gas and liquid in the evaporator conduit, the pump portion per se, is balanced by the relatively high density solid column of liquid in the storage vessel and the liquid supply connections therefrom to the evaporator. In this application the term "gas lift" is to be construed as meaning a pumping or elevating mechanism operating in the manner described immediately above.

A twin gas lift pump or twin gas lift action differs from the more conventional simple gas lift pump or simple gas lift action in that there are two gas lift pumping conduits per se which are joined to each other in a manner to provide a chamber filled with liquid, which liquid will oscillate between the two pumping columns per se as pumping gas is applied to these columns. It is this oscillating body or piston of liquid which is believed to be primarily responsible for the remarkable efficiency of the twin gas lift arrangement as compared with a simple gas lift arrangement.

Due to the fact that the fresh liquid refrigerant supplied from the conduit 28 and the recirculated liquid refrigerant flowing through the conduit 54 each flow directly to the bottom portion of the vessel 28, the liquid in that bottom portion of the vessel contains the largest percentage of the heavier absorption solution and the liquid in the upper portion of the vessel 28 contains relatively pure liquid refrigerant. Therefore, there is a continual though very slow removal of solution from the bottom portion of the vessel 28 through the conduit 60 into the strong solution return line 23. This arrangement prevents the concentration of absorption solution in the liquid circulating through the evaporator and vessel 28 from reaching a value sufficiently high to interfere with proper evaporation and production of refrigeration. Also the arrangement including the conduit 60 prevents the liquid level within the vessel 28 from reaching too high a level.

The liquid which is continuously circulating through the evaporator becomes very cold wherefore the contents of the vessel 28 are very cold

and for this reason it is advisable to insulate the vessel 28 or preferably to embed the same in the insulated rear wall of the customary insulated storage refrigerator cabinet storage compartment. This prevents a decrease in the efficiency of the system by warming of the body of liquid contained in the vessel 28, which in effect acts as a cold accumulator for the entire system.

The liquid refrigerant and inert gas circulates through each section of the evaporator by gas lift action; that is alternate slugs of gas and liquid travel upwardly through the evaporator portions 35 and 36 from the U-shaped conduit 47 to the conduit 30. As a result of this action each slug of liquid leaves a thin film of liquid refrigerant along the wall of the evaporator conduit which liquid of course immediately partially evaporates into the succeeding body of inert gas. Thus refrigeration is produced by evaporation of a thin film of liquid refrigerant which covers the entire inner wall of the evaporator conduit directly into a stream of inert gas flowing through the evaporator.

This thin continuous film of liquid with which the gas is in intimate and continuous contact is provided without introducing any structure of any nature into the interior of the evaporator and without introducing therein anything which would tend to impede heat transfer or free flow of gas and liquid therethrough.

Due to the fact that the liquid refrigerant is supplied to the bottom portion of the evaporator and is elevated therethrough by the inert gas the relative position of the evaporator E and of the condenser C are independent within practical limits. For example, it is not necessary that the upper portion of the condenser be positioned at an elevation above the upper portion of the evaporator. On the contrary the condenser C may extend substantially to the level of the bottom portion of the vessel 28 which is only slightly higher than the bottom portion of the U-shaped conduit 47.

All fluids in the system are circulated by the inert gas; that is, the absorption solution is circulated by the gas lift pump 17 and the liquid refrigerant is circulated through the evaporator by twin gas lift action, thereby assuring that the rates of circulation of all fluids in the system will be properly proportioned relative to each other and relative to the rates with which the inert gas is circulated.

By providing a twin gas lift pump arrangement in the evaporator the efficiency of the apparatus is greatly enhanced and the design of the evaporator is rendered relatively flexible. It is characteristic of this type of pump or circulator that with a given depth of immersion, density of fluids and pressure differential between the gas inlet and outlet portions of the pump, that a twin gas lift pump will circulate a larger quantity of liquids through a given height or a fixed quantity of liquid through a greater height than would be possible with the conventional single pump arrangement.

Accordingly there is provided an absorption refrigerating system in which all fluids are circulated by gas lift action, in which provision is made for a continuous purge of the evaporator system to relieve the same of foreign materials such as absorption solution and in which evaporation occurs from a thin continuous film of refrigerant covering the entire inner surface of the evaporator. There is a direct heat transfer between the wall of the evaporator and the liquid

refrigerant without the intervention of any interior construction in the evaporator and without impeding the flow of gas and liquid therethrough. Another feature of the invention resides in the fact that the large cold body of liquid refrigerant which is present in the evaporator and in the storage purging vessel has a stabilizing influence on the system and tends to reduce the frequency of the operative periods of the apparatus when the same is operated as an intermittent cycle system.

Though the invention has been illustrated and described in considerable detail, it is not to be construed as being limited thereto as various changes may be made in the construction, proportion, arrangement of parts without departing from the spirit of the invention or the scope of the appended claims.

I claim:

- 20 1. Refrigerating apparatus comprising a cooling unit including a pair of individual sections, each of said sections being connected to each other and to a common source of supply of cooling medium, and common means for introducing an inert gas into the cooling medium supplied to each of said sections to circulate the cooling medium therethrough by twin gas lift action.
- 25 2. Absorption refrigerating apparatus comprising a solution circuit including an absorber and a boiler, a pressure equalizing medium circuit including an evaporator and said absorber, means for supplying refrigerant vapor generated in said boiler to said evaporator in liquid phase, means for circulating the pressure equalizing medium through said pressure equalizing medium circuit, gas lift means for circulating the solution through said solution circuit, and means for supplying pressure equalizing medium to said gas lift means to operate the same, said evaporator being constructed and arranged to operate as a twin gas lift pump for the circulation of liquid refrigerant therethrough.
- 30 3. Absorption refrigerating apparatus comprising a solution circuit including an absorber and a boiler, a pressure equalizing medium circuit including an evaporator, a storage vessel and said absorber, means for liquefying refrigerant vapor generated in said boiler, means for circulating the pressure equalizing medium through said pressure equalizing medium circuit, said evaporator comprising a pair of parallel connected continuous conduits, said storage vessel being connected to the inlet and outlet portions of each of said evaporator conduits and arranged to hold a quantity of liquid refrigerant, means for supplying liquid refrigerant from said storage vessel and from said liquefying means to a portion of said evaporator common to each of said conduits, and common means in said pressure equalizing medium circuit for introducing pressure equalizing medium into the portions of each of said parallel connected evaporator conduits which receive refrigerant liquid whereby said conduits operate as a twin gas lift pump to circulate the refrigerant from said storage vessel.
- 35 4. Absorption refrigerating apparatus comprising a solution circuit including an absorber and a boiler, a pressure equalizing medium circuit including an evaporator, a storage vessel and said absorber, means for liquefying refrigerant vapor generated in said boiler, means for circulating the pressure equalizing medium through said pressure equalizing medium circuit, said evaporator comprising a pair of parallel connected
- 40
- 45
- 50
- 55
- 60
- 65
- 70
- 75

continuous conduits, said storage vessel being arranged to hold a quantity of liquid refrigerant and being connected to the inlet and outlet portions of each of said evaporator conduits, means for supplying liquid refrigerant from said vessel and from said liquefying means to each of said evaporator conduits, means in said pressure equalizing medium circuit for introducing pressure equalizing medium into the portion of each of said conduits which is supplied with refrigerant liquid, whereby the same will operate as a twin gas lift pump to circulate liquid refrigerant from said storage vessel, and means for continuously conveying a small quantity of liquid from the bottom portion of said storage vessel into another portion of the system normally containing liquid refrigerant.

5. Refrigerating apparatus including an evaporator comprising a pair of continuous conduits shaped to form a plurality of horizontal coils, a U-shaped conduit connected to the bottom portion of each of said evaporator conduits, means for supplying liquid refrigerant to the bight portion of said U-shaped conduit, and common means for introducing inert gas into the rising portions of each leg of said U-shaped conduit.

6. Refrigerating apparatus comprising a tubular evaporator including a pair of individual sections, a U-shaped conduit connected to the inlet portion of each of said sections, a storage and re-circulation vessel connected to the upper outlet portion of each of said evaporator sections, a U-shaped liquid seal conduit to convey liquid from said vessel into the bight portion of said U-shaped conduit, an inverted U-shaped conduit connected to each of the legs of said first-mentioned U-shaped conduit, means for introducing an inert gas into the bight portion of said inverted U-shaped conduit, means within said vessel for separating gas and liquid supplied thereto from the upper portion of said evaporator, means for removing gas from said separation vessel, and means for supplying fresh liquid thereto.

7. Refrigerating apparatus comprising a tubular evaporator, a liquid refrigerant supply means, a vessel connected to each end of said evaporator and to said liquid refrigerant supply means and arranged to supply liquid refrigerant to said evaporator, means for introducing an inert gas into the liquid refrigerant supplied to said evaporator to circulate the liquid refrigerant therethrough by gas lift action, and means for substantially continuously removing material from the bottom portion of said vessel into said liquid refrigerant supply means.

8. Absorption refrigerating apparatus comprising an inert gas circuit including an absorber, a circulation and storage vessel and an upstanding evaporator conduit, a solution circuit including a generator and said absorber, said circulation and storage vessel having its upper and lower portions connected to the upper and lower portions respectively of said evaporator conduit, means for supplying refrigerant vapor produced in said generator to said vessel in liquid phase, said inert gas circuit being so constructed and arranged that the inert gas is introduced into said evaporator conduit in a manner to circulate the liquid refrigerant therethrough by gas lift action, and means for draining the material at the extreme bottom portion of said vessel into said solution circuit whenever the level of the liquid in said vessel exceeds a predetermined value, said last mentioned means

including an inverted U-shaped conduit having one end terminating within said vessel adjacent the bottom thereof and its other end connected to said solution circuit, and means venting the bight portion of said U-shaped conduit to the upper gas containing portion of said vessel.

9. Absorption refrigerating apparatus comprising an inert gas circuit including an absorber, a circulation and storage vessel and an evaporator conduit, a solution circuit including a generator and said absorber, said circulation and storage vessel having its upper and lower portions connected to the upper and lower portions respectively of said evaporator, means for supplying refrigerant vapor produced in said generator to said vessel in liquid phase, a power driven means for circulating the inert gas through said inert gas circuit in such fashion that the liquid refrigerant is circulated through said evaporator thereby, syphon means for draining the material at the extreme bottom portion of said vessel into said solution circuit whenever the level of the liquid in said vessel exceeds a predetermined value, and means for venting said syphon means to the upper gas containing portion of said vessel in such fashion that said syphon means will cease to function immediately the liquid level in said vessel is reduced below said predetermined value.

10. Refrigerating apparatus comprising a pair of evaporators constructed of unobstructed conduits, means providing for free and unobstructed communication between said evaporators at the lower ends thereof, a source of supply of refrigerant common to each of said evaporators, means for introducing a pressure equalizing medium into the liquid refrigerant in each of said evaporators to raise the refrigerant therethrough by twin gas lift action whereby the gas flows through each of said evaporators in contact with films of the refrigerant on the inner walls thereof.

11. Absorption refrigerating apparatus comprising a solution circuit including a generator and an absorber, a pressure equalizing medium circuit including said absorber, a pair of evaporators constructed of unobstructed conduits in free and open communication at their lower ends and connected to a finned air cooling evaporator at their upper ends and a vessel having open communication with the connected ends of said pair of evaporators at its lower end and with said finned evaporator at its upper end, and power driven means for propelling the pressure equalizing medium through its circuit, said pressure equalizing medium circuit including means for introducing pressure equalizing medium into that portion of each of said pair of evaporators to which liquid refrigerant is supplied whereby the refrigerant is circulated therethrough by twin gas lift action.

12. Refrigerating apparatus comprising a cooling unit including a pair of like sections each of which is constructed of tubing shaped to form a plurality of shelf-like sections serially connected by riser sections, a U-shaped conduit having each leg thereof connected to the lower end of one of said conduit sections, means for supplying a cooling medium to said U-shaped conduit, and means for introducing a pumping gas into each leg of said U-shaped conduit to circulate the cooling medium through said cooling unit by gas lift action.

13. Absorption refrigerating apparatus comprising an absorber, and a pair of upstanding con-

duits constructed and arranged to form a twin gas lift pump evaporator, a solution circuit including a generator and said absorber, a circulation and storage vessel having its upper and lower portions connected to the upper and lower portions respectively of said evaporator conduits, means for supplying refrigerant vapor produced in said generator to said vessel in liquid phase, means for introducing inert gas into said evaporator conduits in a manner to circulate the liquid refrigerant therethrough by twin gas lift action, means for conveying gas and liquid which has traversed said evaporator conduits to said absorber and said vessel, respectively, and means for draining the material at the extreme bottom portion of said vessel into said solution circuit

whenever the level of the liquid in said vessel exceeds a predetermined value.

14. Refrigerating apparatus comprising a cooling unit including a pair of sections in open communication with each other at one end thereof, means for supplying a cooling medium to the communicating ends of said sections, and means for introducing an inert gas into each of said sections adjacent the communicating ends thereof to circulate the cooling medium therethrough by twin gas lift action, said means for introducing inert gas into said sections being so constructed and arranged that open communication is provided between each of said sections through said inert gas introducing means.

ALFRED G. GROSS.
